BEAM-VELOCITY CONTROL SYSTEM FOR
CATHODE-RAY TUBESRichard G. Clapp, Haverford, Pa., assignor to
Philco Corporation, Philadelphia, Pa., a cor-
poration of Pennsylvania

Application November 5, 1946; Serial No. 707,855

1. Claim. (Cl. 178—7.5)

The invention herein described and claimed relates to cathode-ray tube systems and circuits, and, more particularly, to novel circuit means and arrangements for effecting a control function over a cathode-ray beam or beam trace as it moves across the face of a cathode-ray tube. The invention has important application in connection with cathode-ray oscilloscopes and in the picture reconstituting elements of television receivers and the like.

In most applications of the cathode-ray oscilloscope to the observation of voltage or current wave-forms it is desired that the cathode-ray beam be caused to move in a given direction, e. g. from left to right, at constant velocity, so that the horizontal axis of the oscilloscope screen may be utilized as a linear time scale. Against this scale the amplitudes of variable electrical quantities may be displayed as vertical deviations in the trace.

In television picture-reconstituting systems, employing cathode-ray tubes provided with the usual horizontal and vertical deflection circuits, and with means for modulating the electron beam intensity in accordance with the video signal, it is particularly important that the velocity of the beam, as it moves from left to right, be held substantially constant, since otherwise serious distortions in picture geometry will occur.

In certain other applications of the cathode-ray tube, and particularly in oscilloscope work, it is preferred that the horizontal component of beam velocity vary non-linearly with respect to time. For example, in observing certain classes of variable quantities it may be convenient to display the variable against a logarithmic scale or time base.

In accordance with the present invention novel means are provided for precisely controlling a coordinate component of velocity of a cathode-ray beam or beam trace. The invention contemplates not only such controls as will effect a constant velocity of beam movement, but also such controls as will effect predetermined, variable, beam velocities.

It is an object of the present invention to provide a cathode-ray tube circuit arrangement by means of which the velocity of scan may be readily predetermined and precisely controlled.

It is another object of the invention to provide a projection system of television picture reconstitution in which light from the primary picture source, heretofore wasted or unused, is utilized to influence or control the reconstitution of the television picture.

2.

It is another object of the invention to provide a deflection-control circuit for use with cathode-ray tube systems, by means of which the provision and maintenance of a timing axis of great precision may be achieved.

It is still another object of the invention to provide a deflection control circuit, for use with cathode-ray oscilloscopes, by means of which successive and equal time intervals may be presented, along the timing axis, by successively varying space intervals.

These and other objects of the invention, and the manner in which they are attained, will appear from the following detailed description and the accompanying drawings, in which

Fig. 1 is a diagrammatic illustration of a preferred embodiment of the invention;

Fig. 2 is an illustration of a mask used in conjunction with the photo-electric cell shown in Fig. 1; and

Fig. 3 is a fragmentary illustration showing a modification of a part of the system illustrated in Fig. 1.

Reference may now be had to Fig. 1 in which there is illustrated, diagrammatically, a cathode-ray tube system employing the principles of the present invention. It will be assumed, for purposes of description, that the system illustrated constitutes a portion of the picture-reconstituting apparatus of a television receiver, but it will be apparent that the apparatus described is equally adapted for use in cathode-ray oscilloscopes, and the like. The system illustrated includes a number of conventional devices conventionally arranged. These include the cathode-ray picture tube 1, deflection coil assembly 2, horizontal discharge-tube circuit 3 (preferably of high internal impedance) constructed and arranged to develop a sawtooth voltage wave ϵ across the capacitor C, a horizontal output pentode 4, and a coupling transformer 5 by means of which a sawtooth current wave is introduced into the horizontal deflecting coil contained within assembly 2. The vertical deflecting system, which may be conventional, has been omitted from the drawing in the interests of simplicity. The spherical mirror 6 and the aspherical correcting lens 7 comprise elements of a Schmidt system of television picture projection adapted to project the primary image, appearing on fluorescent screen 8, onto a suitable viewing screen S positioned rearwardly of the cathode-ray tube 1. Detailed information relating to projection systems of this type is available in the article by Maloff and Epstein, appear-

ing in the December 1944 issue of "Electronics," pp. 98-105.

In accordance with the present invention there are provided means, responsive to the movement of the beam spot as it crosses screen 8, for generating an alternating voltage whose frequency is proportional to the velocity of said spot. Co-operating means are provided, responsive to the frequency of said voltage, for generating a correcting signal which is utilized, in conjunction with the normal deflecting current, to correct or control the velocity of said beam spot in a manner such as to maintain said frequency substantially constant. In the embodiment illustrated in Fig. 1, the foregoing means are comprised of the devices and circuits now to be described.

In the central aperture conventionally provided in the center of the spherical mirror 6 there is mounted a suitable lens 9 which is adapted to project the primary image or picture appearing on the screen 8 onto the sensitized face 10 of a photo-electric cell 11. Lens 9 is preferably coated to prevent reflection of incident light back onto the screen 8. The cell 11 may be, for example, a photovoltaic cell in which a voltage is generated in a layer of selenium during exposure to light, or it may comprise a vacuum-type photo-cell having a substantially rectangular, flat cathode. The light-sensitive face 10 of the photo-electric cell is provided with a vertically apertured mask 12, such as that illustrated in Fig. 2, comprising a plurality of alternately opaque and transparent areas. Accordingly, as the brilliant, rapidly moving spot travels horizontally across the screen 8 the photo-electric cell 11 is excited intermittently and generates a voltage whose frequency, in megacycles per second, is equal to the number of transparent lines encountered by the moving spot per microsecond of spot travel. Since the flyback time is small compared to the horizontal line period this frequency will approximate the horizontal line frequency multiplied by the number of transparent mask apertures traversed by the spot in one line scan. In a television system operating under the present standard of 525 lines, thirty frames per second, the frequency of the signal developed during the normal line period will be of the order of 3.15 megacycles per second for a system in which the mask 12 comprises 200 apertures.

During the return-line, or flyback, period the beam spot is extinguished by the application of the usual blanking signal (details not shown) and in consequence no signal is generated during such period. If the blanking should not be complete during this period there would be developed in photo-electric cell 11 a second alternating current voltage of much higher frequency, but the presence of this voltage would not affect the operation of the system, since the devices 14 and 15, now to be described, are substantially non-responsive to this higher frequency.

The alternating current voltage developed in the photo-electric cell 11 is applied, by way of conductor 13, to a frequency modulation discriminator or detector 14 which is preferably tuned to the frequency of the voltage developed by the photo-electric cell 11 when the spot velocity is that desired for normal operation of the system. Where the electron beam is intensity-modulated, as it is in conventional television receivers, the frequency modulation detector 14 is preferably of a type which is non-responsive to amplitude modulation, since, under the conditions mentioned, the voltage generated in the cell 10 is

amplitude modulated in accordance with the intensity modulation of the cathode-ray beam. The frequency modulation detector disclosed in the copending application of W. E. Bradley, Serial No. 576,057, filed February 3, 1945, and assigned to the Philco Corporation, is particularly advantageous in the present system. A conventional frequency detector may be employed, however, if, as illustrated, a suitable amplitude limiter 15 is interposed between the photo-electric cell and the detector.

The output of the frequency modulation detector 14 is a voltage (or current) whose magnitude and polarity is a function of the direction and extent of deviation of the spot velocity from its preassigned velocity. A low pass filter 16 is preferably provided in the output circuit of the frequency modulation detector 14 for the purpose of rejecting any high frequency signal that may be present in the output circuit of the detector 14. The constants of the frequency modulation detector 14—or of the frequency modulation detector 14 in combination with the low pass filter 16—are preferably such that the arrangement possesses high internal resistance and functions, accordingly, as a current generator. In this respect, the detector described in the above-identified copending application of W. E. Bradley is ideal.

The output circuit of low pass filter 16 is connected in shunt with the capacitor C across which the sawtooth voltage e_s , hereinbefore referred to, is developed. Thus connected the output current of the frequency modulation detector 14 acts to vary the charge contained in the capacitor C, and so tends to control the wave shape of the voltage e_s . As indicated above, the output current of the frequency detector is proportional, in magnitude, to the deviation of the spot velocity from the preassigned velocity. And, by proper choice of detector output circuit connections, the polarity of the detector output is such that if the spot moves too slowly, the capacitor C charges more rapidly, while, if the spot moves too rapidly, the capacitor C charges more slowly. In either case the tendency is to correct deviations from the preassigned spot velocity. In other words, the effect of the feedback path comprising photocell 11 and detector 14 is to so control the velocity of the beam spot as to effect the generation of a signal of constant frequency by the photo-electric cell 10, which, in this case, means constant beam velocity.

Should the picture appearing on screen 8 of picture tube 1 contain black areas which are completely dark, there will, of course, be corresponding time intervals during which no moving spot of light will traverse the photocell. Such completely dark areas are rare in practice however and the photocell will normally receive the illumination necessary to generate a voltage capable of driving the detector 14. However if the voltage generated in the photocell is insufficient to drive the detector it is to be noted that the presence of the feedback path cannot in any way interfere with the normal, uncompensated operation of the horizontal discharge tube circuits.

Attention is directed to the fact that, in projecting the primary image (i. e. the picture appearing on fluorescent screen 8) onto the photocell 11, no light is taken from the projection tube 1 which might otherwise be useful in the projection of the primary picture onto the viewing screen S. In previous projection systems of the

type illustrated the light directed toward the central region of the spherical mirror 6 has been entirely wasted because such light is prevented from reaching the viewing screen by the intervening presence of the projection tube. In fact, in order to prevent deleterious reflections of light from the aforesaid central region of the mirror 6 back onto the fluorescent screen of the projection tube, it has been the practice to blacken this central region, or, alternatively, to provide an aperture therein as illustrated in Fig. 1. It is apparent, therefore, that in accordance with one of the features of this invention, apparatus is provided by means of which light heretofore wasted is utilized to influence or control the reconstitution, or, more specifically, the geometry of the primary television image.

Reference may now be had to Fig. 3, in which there is illustrated a modification of that portion of the system of Fig. 1 which comprises the cathode ray tube and the elements associated immediately therewith. In Fig. 3 those elements which correspond identically to elements in Fig. 1 are identified with corresponding reference characters. The arrangement of Fig. 3 is particularly adapted for use with direct-viewing television receivers and with direct-viewing cathode ray oscilloscopes where the projection apparatus 6-7 of Fig. 1 is not present. While, in the illustration, deflection of the cathode ray beam is accomplished magnetically through the agency of deflecting currents supplied to yoke 2 by the usual horizontal and vertical deflection circuits (the latter not shown), it will be apparent that a conventional electrostatic deflection arrangement may be substituted if desired.

In the embodiment of Fig. 3, there is provided, in place of the photo-electric cell arrangement of Fig. 1, a conducting grid 18 engaging either the inner or outer surface of face 19 of cathode ray tube 20. The number and arrangement of individual conductors 21 comprising the grid is controlled by the same factors which control the number and spacing of the apertures in the mask 12 of Fig. 2. Grid 18 is conveniently applied to the face of tube 20 by a suitable evaporation process, employing a stencil or mask to control the character or configuration of the grid. The metal (e. g. aluminum) comprising the grid may, if desired, be evaporated onto face 19 in such a thin layer as to be substantially invisible to the eye. The individual grid wires 21 are connected together by means of a horizontal conducting element 22 which, in turn, is connected to the input circuit of frequency modulation detector 14 by way of conductor 13.

Where the grid 18 is positioned on the outer surface of tube-face 19, the grid derives an electrical impulse from the cathode ray beam, through capacitive coupling therewith, whenever said beam passes directly beneath a grid conductor. Accordingly there will appear on the common conductor 22 an alternating voltage whose frequency is a function of the beam velocity and of the spacing of the individual grid conductors 21. This voltage is applied to detector 14 by way of conductor 13, and the control of beam velocity is then accomplished as described hereinbefore with reference to Fig. 1.

If grid 18 be positioned on the inner surface of tube-face 19 (e. g. between the glass and the phosphor), the grid derives an electrical impulse from cathode ray beam, largely through conductive coupling therewith, whenever the beam im-

pinges on a portion of the phosphor overlying one of the grid conductors.

In some instances it may be desirable to provide a time base or axis in which equal divisions or units of time are displayed as unequal distances along the axis. A logarithmic time base, for example, is frequently convenient in radar "A" scope presentations and in plan position indicators. Such a logarithmic time base may easily be provided by means of a grid 18 whose individual grid elements 21 are logarithmically spaced along the common conductor 22 as illustrated in Fig. 3.

In general, the shape of the deflecting current wave e_c (Fig. 1) should roughly approximate that necessary to provide the type of deflection desired, but the precise shape of the wave is not important since the circuits of the present invention can be relied on to compensate for very substantial irregularities in the wave-form supplied by the horizontal discharge tube circuits.

It will be apparent that, through the utilization of the principles of the present invention, deflection wave shapes of virtually any desired form can be attained by the provision of suitably designed masks or grid. In this way special time bases may be provided which otherwise might be very difficult of attainment.

In the foregoing the instant invention has been described with particular reference to certain specific, illustrated embodiments; it will be apparent to those skilled in the art, however, that various alternative arrangements may be employed within the scope of the invention defined in the appended claim.

I claim:

In a television receiver, a cathode-ray picture tube having means for forming a cathode-ray beam, means for deflecting said beam horizontally at an approximately constant velocity, means including a photo-electric cell and a grating positioned externally of said picture tube for generating an alternating voltage whose frequency is a direct function of the horizontal component of beam velocity, amplitude-insensitive frequency-responsive means for generating a control current whose magnitude and polarity are substantially direct functions of the deviation of said frequency from a preassigned reference frequency, and means responsive to said control current and operative upon said deflecting means to minimize said deviations.
